(57) CLAIM

The ornamental design for a bench, as shown and described.

DESCRIPTION

FIG. 1 is a front, right and top perspective view of a bench, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, right and top perspective view of the bench, shown in an alternative position; and,

FIG. 10 is another rear, left and bottom perspective view thereof.

The broken lines in the drawings depict portions of the bench that form no part of the claimed design.

1 Claim, 10 Drawing Sheets
